John F. Harrison and Carl F. Greiner, Springfield, Ohio, assignors to The Buffalo-Springfield Roller Co., Springfield, Ohio, a corporation of Ohio

Application May 1, 1944, Serial No. 113,422

Term of patent 14 years

(Cl. D14—3)

To all whom it may concern:

Be it known that we, John F. Harrison and Carl F. Greiner, citizens of the United States, residing at Springfield, county of Clark, State of Ohio, have invented a new, original, and ornamental Design for a Road Roller, of which the following is a specification, reference being had to the accompanying drawings, forming a part thereof.

In the drawings—

Fig. 1 is a side elevational view of a road roller, showing our new design.

Fig. 2 is a top plan view thereof.

Fig. 3 is a rear elevational view, the seat and levers shown in Figs. 1 and 2 having been omitted for convenience of illustration.

Fig. 4 is a front elevational view thereof, the seat and levers shown in Figs. 1 and 2 having been omitted for convenience of illustration.

We claim:

The ornamental design for a road roller, substantially as shown.

JOHN F. HARRISON.
CARL F. GREINER.
